UNITED STATES PATENT OFFICE.

JOHN G. KELLER, OF MILWAUKEE, WISCONSIN, ASSIGNOR TO THE VILTER MANUFACTURING COMPANY, OF MILWAUKEE, WISCONSIN, A CORPORATION OF WISCONSIN.

STEAM-ENGINE.

1,389,832.

Specification of Letters Patent.

Patented Sept. 6, 1921.

Application filed August 27, 1917. Serial No. 188,395.

To all whom it may concern:

Be it known that I, JOHN G. KELLER, a citizen of Switzerland, residing at Milwaukee, in the county of Milwaukee and State 5 of Wisconsin, have invented certain new and useful Improvements in Steam-Engines, of which the following is a specification, reference being had to the accompanying drawing, forming a part thereof.

10 This invention relates more particularly to medium speed puppet valve engines, simple, cross or tandem compound, designed for the use of high pressure superheated steam.

15 The main objects of the invention are to simplify the construction of the valve gear and valve actuating connections, the lay shaft with its noisy bevel gears and its multiplicity of bearings and eccentrics for the 20 individual valves, as commonly used in connection with puppet valve engines, being eliminated; to reduce the consumption of steam and fuel; and generally to increase the efficiency and improve the construction and 25 operation of engines of this class.

The invention consists in the construction, arrangement and combination of parts as hereinafter particularly described and pointed out in the claims.

30 In the accompanying drawing like characters designate the same parts in the several figures.

Figure 1 is a side elevation of a portion of a steam engine embodying the invention; 35 Fig. 2 is an end elevation as viewed from the right relative to Fig. 1; Fig. 3 is a vertical longitudinal section of the cylinder and valve housings; Fig. 4 is an enlarged vertical section of one of the exhaust valves 40 and associated parts of the engine; Fig. 5 is a similar view of one of the admission valves and associated parts; Fig. 6 is an enlarged plan view of the admission valve releasing gear at one end of the cylinder, 45 and a partial horizontal section of the bonnet on the line 4—4, Fig. 1; and Figs. 7 and 8 are enlarged sectional detail views of a disengaging device for disconnecting the valve gear from the actuating eccentric on 50 the crank shaft of the engine, Fig. 7 being a section on the line 7—7, Fig. 8, and Fig. 8 a section on the line 8—8, Fig. 7.

The engine comprises a cylinder 1, which may be the single cylinder of a simple en-

gine, or the high pressure cylinder of a 55 cross or tandem compound engine. It is formed, as shown in Figs. 3 and 4, on the under side adjacent to the ends and transversely to the axis of the cylinder, with valve pockets 2, into the inner ends of which 60 the exhaust ports 3 open, and from which exhaust passages 4 lead laterally toward the middle of the cylinder to exhaust pipe connections 5.

The cylinder is provided with detachable 65 hollow or chambered heads 6 and 7, each formed, as shown in Figs. 3 and 5, on the upper side transversely to the axis of the cylinder, with an admission valve chamber 8, communicating at one side above the valve 70 seats, with the steam chambers 9, which communicate on their lower sides through passages 10 with steam supply pipes or connections 11. The steam and exhaust connections being separate from one another, avoid 75 unequal and injurious strains on the cylinder resulting from the high temperature of the superheated steam with which the hollow heads are supplied, and the lower temperature of the exhaust steam passing 80 through the exhaust ports, valve pockets and passages formed in the cylinder. Steam admission ports 12 are formed in the cylinder heads and lead laterally from the inner ends of the pockets 8 below the valve seats there- 85 in, directly into the ends of the cylinder.

Cages 13, each formed in parallel planes with two valve seats 14 and 15, are fitted in the pockets 8 and are formed or provided 90 with axial valve guides 16.

Cover plates 17 are bolted or otherwise detachably secured with bonnets 18 to the cylinder heads over the pockets 8, closing the outer ends thereof. The plates 17 are provided with sleeve bearings 19 in axial 95 alinement with the valve guides 16, and the bonnets 18 are formed with bearings 20 in axial alinement with the sleeve bearings 19. On the upper sides of the bonnets in axial alinement with said bearings, are formed 100 dash pots 21, and on the dash pots are detachably mounted spring cases or housings 22.

Balanced double-beat puppet valves 23, fitted to the seats 14 and 15 and to the guides 105 16 in the cages 13, are provided with stems 24, fitted and guided in the sleeve bearings 19 and formed with labyrinth packing grooves

within said bearings. To the upper ends of the stems 24 are attached yokes 25, formed or provided with upwardly extending stems 26, in alignment with the stems 24 and constituting in effect continuations thereof.

Check pistons 27, fitting in the dash pots 21, are formed or provided with tubular stems 28, which are secured on the stems 26 and are guided in the bearings 20. The dash 10 pots 21 are provided at or near the bottom thereof with air check valves 29, for regulating the air cushions against which the valves 23 close.

Springs 30, interposed between seats 31 attached to the upper ends of the stems 26 and vertically adjustable seats 32 in the upper ends of the housings 22, tend to close the valves 23. The spring seats 32 bear against, and the tension of the springs 30 is 20 adjusted, by screws 33, threaded in the upper ends of the housings 22 and secured in place therein by lock nuts.

The admission valves 23 are opened by lifting arms 34, pivoted to slide blocks 35 in the yokes 25 and fixed on rocker shafts 36 mounted in the bonnets 18, transversely to the valve stems and to the axis of the cylinder. The rocker shafts 36 are actuated to open the valves by releasing gear from 30 an eccentric (not shown) on the crank shaft of the engine under the control of a centrifugal governor 37, shown in Fig. 1.

The automatic variable cut-off releasing gear for the operation of the steam admission valves 23, comprises, as shown in Figs. 1, 2 and 6, an arm 38, fixed on the rocker shaft 36, a lever 39 fulcrumed on an extension of the bonnet 22 coaxially with and adjacent to the arm 38, a hook or dog 40, pivotally mounted on the lever 39, and movable into and out of position to engage with the arm 38, a trip arm 41, fixed on the pivot pin or shank of the hook or dog, a spring 42, attached to the trip arm and 45 tending to hold the hook or dog in position to engage with the arm 38, and a knock-off or trip cam 43, rotatably mounted on the extension of the bonnet 22 coaxially with the rocker shaft 36, and movable in 50 the path of the trip arm 41 to release the admission valve 23 and permit it to close at any point in the travel of the engine piston, from zero to about nine tenths of full stroke. The trip cams 43 may be connected 55 with the governor 37 in any suitable manner.

As shown in Fig. 1, an upwardly extending arm 44 on the cam at the front end of the cylinder, is connected by a rod 45 with the governor lever 46, and a downwardly 60 projecting arm 47 on the front cam is connected by a rod 48 with an upwardly projecting arm 44 on the rear cam.

As shown in Fig. 5, each valve stem 24 is lubricated by a force feed oil connection 65 49, with the upper part of the sleeve bearing

19, a passage 50 leading downwardly from said connection into the bore of the bearing.

An outlet pipe or connection 51, leading from a chamber formed around the valve stem 24 in the sleeve bearing 19 adjacent to 70 its upper end, conducts off surplus oil and water formed by the condensation of steam in the labyrinth grooves of the valve stem, the oil and water held in the grooves making a steam tight joint between the valve stem 75 and sleeve bearing.

The admission valves are opened under the control of the governor by a more or less direct connection with an eccentric (not shown) on the crank shaft of the engine, 80 thus eliminating the ordinary lay shaft with its noisy bevel gears and multiplicity of bearings and eccentrics or cams, and enabling the puppet admission valves of the high pressure cylinder of a tandem compound engine to be operated by the same eccentric which operates the admission valves, Corliss or puppet, of the low pressure cylinder, and controlled by simple governor connections, according to the usual practice in 85 Corliss engine design and construction.

As shown in Figs. 1 and 2, the levers 39 are connected by rods 52 with a wrist plate or rocker 53, which is connected by a detachable coupling device 54 with the eccentric 95 rod 55 or a rod actuated directly or indirectly by an eccentric on the crank shaft of the engine.

As shown in Figs. 3 and 4, cages 56 fitted in the exhaust valve pockets 2 of the cylinder, are each formed with two valve seats 57 and 58, and provided with an axial sleeve bearing 59, the upper end of which extends above the lower valve seat and forms a valve 100 guide.

Bonnets 60, bolted or detachably fastened to the cylinder over the pockets 2, confine the cages 56 in place therein, and are formed with guides or bearings 61 in axial alignment or parallel with the sleeve bearings 59. 105

Balanced double-beat puppet exhaust valves 62, like or similar to the admission valves 23, are fitted to the guides on the upper ends of the sleeve bearings 59 and are adapted to close simultaneously on the seats 57 and 58. The valves 62 are provided with stems 63, fitted in the sleeve bearings 59 and formed therein with labyrinth packing grooves, as shown in Fig. 4.

To the lower ends of the stems 63 are fastened yokes 64, fitted in the guides or bearings 61 and provided with rollers 65. To the lower ends of the yokes 64 are attached, in alignment with the valve stems 63, stems 66, to the lower ends of which are adjustably fastened spring seats 67. Springs 68, interposed between the lower ends of the bonnets 60 and the seats 67, tend to close the valves 62 and hold them on their seats.

Rocker shafts 69, having bearings in the 130

bonnets 60 transverse to the valve stems and to the axis of the cylinder are provided with cams 70, adapted by engagement with the rollers 65, to lift and open the valves 62.

- 5 Referring to Fig. 4, a force feed oil supply pipe 71, is connected with the lower end of the sleeve bearing 59 and communicates with a passage 72 leading upwardly into the bore of the bearing adjacent to its 10 upper end. A return or outlet pipe 73, for surplus oil and water of condensation, is connected with said sleeve bearing in communication with an annular chamber formed in the lower part thereof around the valve 15 stem.

- The rocker shafts 69 extend outwardly through one of the cylinder supports 74, on which they have adjustable bearings 75, and are provided at their outer ends with arms 20 76. The arms 76 are connected, as shown in Fig. 1 by rods 77 with a wrist plate or rocker 78, which is connected by a detachable coupling device 54 with a rod 79 directly or indirectly connected with and actuated by an 25 eccentric (not shown) on the crank shaft of the engine.

- The detachable or releasable coupling devices 54, by means of which both the admission and the exhaust valves may be disconnected from the eccentrics on the engine 30 crank shaft and operated manually for warming and draining the cylinder, starting the engine, etc., each comprise, as shown in Figs. 7 and 8, a journal box 80, fitting 35 the wrist pin 81 on one of the rocker arms, and formed transversely to the axis of the wrist pin with a split clamping sleeve 82, normally fitting the actuating eccentric rod 55 or 79 freely, and provided with a clamping 40 screw 83. The screw 83 is provided with an operating handle 84, and is formed on one side with a notch 85, which when it is turned into register with the bore of the sleeve 82, permits the eccentric rod to slide 45 freely therein. The eccentric rod is also formed with a notch 86, into which the clamping screw 83 fits when the notch 85 therein is turned out of register with the bore in the sleeve 82 to lock and hold the eccentric 50 rod in its normal working relation to the wrist pin 81. The box 80, or coupling head, is provided with a spring pressed locking pin 87, having a tapered end fitting into a correspondingly tapered socket 88 in the eccentric rod, to facilitate bringing the cross 55 bore in the sleeve 82 for the clamping screw 83, into exact register with the notch 86 in the eccentric rod, and to assist in holding the coupling head in its exact normal working 60 position on the eccentric rod.

The upper or protruding end of the locking pin 87 is provided with a cross piece or handle 89, for lifting it out of engagement with the socket in the eccentric rod, and is 65 also provided on one side, as indicated by

dotted lines in Fig. 7, with a stud 90, loosely fitting into a groove in one side of a cap screw 91, for holding the locking pin retracted and out of contact with the eccentric rod, the stud being withdrawn from the 70 groove and turned with the pin into engagement with the top or outer face of the cap screw.

To disconnect either set of valves from their actuating eccentric, the handle 84 of 75 the clamping screw is turned up till the notch 85 registers with the bore of the sleeve 82, and the locking pin 87 is withdrawn from the socket 88 and turned to carry the stud 90 into engagement with the outer face of 80 the cap screw 91. The associated valves may then be manipulated by hand through the wrist plate or rocker with which they are connected, the eccentric rod being held and guided by the sleeve 82, in which it is free to 85 reciprocate in case the engine is started.

To reconnect the valves with their actuating eccentric, the locking pin 87 is first released, and being pressed by its spring against the eccentric rod, will be forced into 90 the socket 88 therein when the coupling head 95 80 is brought approximately to its normal position thereon. The forcing of the tapered pin into the tapered socket, brings the coupling head into exact position with the notch 86 in the eccentric rod, in perfect register with the cross bore in the sleeve 82. The handle 84 is then turned down to its normal position, thereby turning the clamping screw 95 into engagement with the notch and clamping 100 the sleeve tightly on the rod.

It will be observed that the lower seats 15 of the admission valves 23, are located in a plane somewhat above and out of alignment with the upper sides of the openings of the admission ports 12 into the cylinder, and that the lower seats 58 of the exhaust valves are located in a plane above and out of alignment with the upper sides of the exhaust 110 passages 4. By this construction and arrangement of the valve seats, ports and passages, side pressure of steam against the valves when they are opened, and unequal wear due to this cause, are avoided.

The cylinder heads are provided with 115 thermometers 92, extending into the admission valve chambers as close as possible to the admission ports, for determining the temperature of the superheated steam as it enters the cylinder.

The cylinder supports 74 are extended beyond the cylinder at its rear end and form supports and guides for the removal of the rear head 7, which is formed or provided with separate feet or brackets 93, resting on 120 said supports, guiding and supporting the head when it is detached from the cylinder in substantial alignment therewith and facilitating removing and replacing the same.

The operation of the engine, valves and 130

valve gear will be understood from the drawing and the foregoing description, without further explanation.

Various modifications in the construction and arrangement of parts of the engine may be made without departure from the principle and scope of the invention as defined in the following claims.

I claim:

- 10 1. In a steam engine the combination with the cylinder and piston, of bonnets mounted on the cylinder, puppet steam-admission and exhaust valves having stems guided in the bonnets, rocker shafts mounted in the bonnets transversely to the valve stems and to the axis of the cylinder and connected with the valve stems, valve opening and variable releasing gear connected with each rocker shaft of the admission valves, wrist plates having connections for actuating the rocker shafts to open the valves, means tending to close the valves, reciprocating eccentric rods arranged lengthwise of the cylinder and releasable couplings for operatively connecting and disconnecting the eccentric rods with the wrist plates, each comprising a clamping sleeve pivoted on a wrist plate and fitted on an eccentric rod, a clamping screw intersecting the bore of the sleeve on one side and adapted by engagement with a notch in the eccentric rod to lock the sleeve in working

position on the rod, the clamping screw being formed in another side with a notch which when turned into register with the bore of the sleeve, releases the rod and permits it to slide freely in the sleeve, and a spring pressed tapered pin fitted in the sleeve and adapted by engagement with a corresponding tapered socket in the eccentric rod, to bring the notch therein into exact register 40 with the cross bore in the sleeve for the clamping screw.

2. In a steam engine the combination of a cylinder provided with valves, valve operating gear comprising a rocker connected with the valves, and a reciprocating rod having a transverse notch in one side, and a coupling for releasably connecting said rod with the rocker comprising a clamping sleeve pivotally mounted on the rocker and fitted on the rod, and a clamping screw intersecting the bore of the sleeve on one side and adapted by engagement with the notch in the rod to lock the sleeve in operative position on the rod, the clamping screw being formed in one 50 side with a notch which when turned into register with the bore of the sleeve releases the rod and permits it to slide freely in the sleeve.

In witness whereof I hereto affix my signature.

JOHN G. KELLER.
